Primary Examiner — Amy C Wierenga*(74) Attorney, Agent, or Firm* — Lucas & Mercanti, LLP(57) **CLAIM**

The ornamental design for connector for fluids, as shown and described.

DESCRIPTION

FIG. 1 is a perspective view of a connector for fluids;

FIG. 2 is a front view thereof; and,

FIG. 3 is a side view thereof.

The broken lines which define the bounds of the claimed design form no part thereof.

1 Claim, 3 Drawing Sheets(56)
